United States Patent Office

Des. 202,865
Patented Nov. 16, 1965

202,865

CABINET FOR ADVERTISING SIGNS OR THE LIKE

Carl T. Brookshire, 4041 44th St., San Diego, Calif.

Filed Aug. 28, 1964, Ser. No. 81,500

Term of patent 14 years

(Cl. D1—11)

FIG. 1

FIG. 2

FIG. 4

FIG. 3

FIG. 1 is an elevational view taken from one side of a cabinet for advertising signs or the like showing my new design, the opposite side being a mirror image of the side shown.

FIG. 2 is a front elevational view thereof;

FIG. 3 is a rear elevational view thereof;

FIG. 4 is a front perspective view thereof.

The broken line showing of advertising copy in FIGS. 1 and 4 is for purposes of illustration only.

I claim:

The ornamental design for a cabinet for advertising signs or the like, as shown and described.
